UNITED STATES PATENT OFFICE.

ERASTUS W. SCOTT, OF WAUREGAN, CONNECTICUT.

DESIGN FOR A WHIP-SOCKET.

SPECIFICATION forming part of Design No. 13,285, dated September 5, 1882.

Application filed August 7, 1882. Term of patent 7 years.

To all whom it may concern:

Be it known that I, ERASTUS W. SCOTT, of Wauregan, in the county of Windham, of the State of Connecticut, have invented or produced a new and original Design for a Whip Socket or Holder for a Wheel-Carriage; and I do hereby declare the same to be described in the following specification, and represented in the accompanying drawing, by which it is shown in side elevation.

The main body *a* of the whip-socket is cylindrical or slightly conical. Its head terminates at top in a molding, *b*, which is an inverted ovolو. Below, and at a short distance from the molding *b* or upright ovolو, is another molding, *c*, and a bead, *d*, at the base thereof. The part *g* between the two ovolos is cylindrical. At its lower part the body *a* terminates in a

foot, *e*, of a conical or approximately conical form, as shown, there being above such foot a 20 bead, *f*, which encircles the body.

I claim—

1. The design, substantially as described, for a whip-socket head, it consisting of the cylindrical part *g*, the two ovolо moldings *b c*, and 25 the bead *d*, as and arranged as described.

2. The design, substantially as described, for the whip-socket, it being composed of the cylindrical or slightly conical body *a*, the ovolо moldings *b c*, beads *d* and *f*, cylindrical part *g*, and 30 conical foot *e*, essentially, and arranged as represented.

ERASTUS W. SCOTT.
